ANKLET

James A. Richardson, Burlingame, Calif.

Application November 14, 1949, Serial No. 6,032

Term of patent 14 years

(Cl. D7—7)

To all whom it may concern:

Be it known that I, James A. Richardson, a citizen of the United States of America and residing at Burlingame, California, have invented a new, original, and ornamental Design for Anklet, of which the following is a specification, reference being had to the accompanying drawing, forming a part hereof.

Fig. 1 is a side elevational view of an anklet showing my new design as it appears when worn, the broken lines being for illustrative purposes only; and

Fig. 2 is a plan view of the anklet in a spread out condition.

I claim:

The ornamental design for an anklet, substantially as shown and described.

JAMES A. RICHARDSON.
